UNITED STATES PATENT OFFICE.

CHARLES P. HIDDEN, OF NEW YORK, N. Y.

EXPRESSION DEVICE FOR PLAYER-PIANOS AND THE LIKE.

1,103,582.

Specification of Letters Patent.

Patented July 14, 1914.

Application filed March 8, 1910. Serial No. 548,039.

To all whom it may concern:

Be it known that I, CHARLES P. HIDDEN, a citizen of the United States, residing at New York city, in the borough of Manhattan and State of New York, have invented certain new and useful Improvements in Expression Devices for Player-Pianos and the like, of which the following is a full, clear, and exact description.

- 10 This invention relates to an expression device for player pianos and like instruments, and has for its object the provision of means in such instruments whereby a performer may accent, if he so desires, any desired note 15 or notes at will, giving such accented notes any desired degree of intensity while playing the remainder of the notes as softly or loudly as desired. The accenting means is manually controllable, if desired, and a 20 further object of my invention is the provision of automatic means for effecting the same result, should the operator not desire to control the selection of the notes to be accented.
- 25 My invention further comprises novel indicating means for showing what portions of the scale are at any given moment acceptable.
- 30 The invention further contemplates the provision of two relatively independent vacuum systems and comprises means for reducing the pressure in one of such systems for modulating the intensity of tone of notes which it is desired not to accent, in- 35 stantaneously subduing the same to the desired extent despite the fact that at the preceding instant the entire mechanism may have been operated to the limit of its power.
- 40 The invention involves many other novel and useful features, which will be herein- 45 after described and set forth in the specification and more particularly pointed out in the claims appended hereto.
- Referring therefore to the accompanying drawings which form a part hereof and in which like characters of reference designate like parts throughout the several views: Figure 1 is a somewhat diagrammatic section taken through the body of the piano, 50 centrally thereof in the lower part of said section, and somewhat to one side of the center in the upper part of said section as per the indicated line of section I—I as in Fig. 2, showing tone producing means and 55 accent controlling devices for operating said tone producing means with any desired in-

tensity. Fig. 2 is a plan of the expression controlling device, which I prefer to support from the under portion of the piano front. Fig. 3 is a front elevation, partly in section, of said device, the sections of the respective sectioned parts being taken on line III—III of Fig. 2. Fig. 4 is an enlarged detail of a valve stem, showing the valves in place thereon. Fig. 5 is a section taken on line V—V of Fig. II. Fig. 6 is a perspective view of a sleeve used in connection with the manually operated shaft. Fig. 7 is a perspective view of the nippled cylinder. Fig. 8 is an enlarged view of a fragment of the same, showing the disposition of the nipples thereon. Fig. 9 is an enlarged transverse section of the indicating device. Fig. 10 is a fragmentary elevation of said device. Fig. 11 is a fragmentary section of a valve chamber. Fig. 12 is a side elevation, showing the pedal parts folded back into the piano casing. Fig. 13 is a diagram illustrating the relative movements of the low and high vacuum bellows when the pedal has traversed one-quarter of its stroke. Fig. 14 is a corresponding diagram when the pedal has traversed three-quarters of its stroke. Fig. 15 is a side view of a portion of the brake mechanism; Fig. 16 shows a fragment of the end of a tracker-board with a piece of roll in position thereupon, the paper being torn away to show the position of the expression device controlling vents. Fig. 17 shows a modification of the valve cylinder; and Fig. 18 is a partial longitudinal vertical median section of the valve chest hereinafter referred to.

Referring to Fig. 1, the usual roll box 1 carries reels 2 and 3 therein, the usual paper strip 4 passing over the tracker 5 and the small tubes 6 leading downward from the said tracker to diaphragmed recesses 7, in the usual manner. The operation of the diaphragm 8 by the admission of air to chamber 7 displaces a valve 9 and throws pneumatic 10 into communication with the exhaust. Pneumatic 10 operates the tone producing device 11, which in this instance is a hammer and string. The diaphragmed chamber 7 is provided with the usual bleed hole 12. Normally the pneumatic 10 is in communication with the outer atmosphere through the port 10', but when the valve 9 is driven to the left, as viewed in Fig. 1, said valve engages the small annular boss 9' at the

mouth of the port or passage 10' and closes the latter to prevent waste of air. When said valve 9 returns to the position in which it is shown in Fig. 1 said port 10' is of course again opened. In so far as we have gone, nothing particularly novel has been presented. In my device, however, the valve chest 13 is divided longitudinally thereof into two compartments 14 and 15; compartment 14 being connected with the high vacuum bellows, and compartment 15 with the low vacuum bellows hereinafter referred to. A series of valve chambers 16 are disposed preferably between compartments 14 and 15. In this exemplification of my invention I have shown in Fig. 11 the respective pneumatic valve stems 17 of said chambers as each controlling the exhaust from a group of three note sounding pneumatics; three adjoining pneumatics exhausting into a common valve chamber 16. A series of vertically disposed valve stems extend substantially throughout the length of the valve chest, one of such stems being provided for each valve chamber 16, and each of said stems carrying thereupon two valves 18 and 19; a valve 18 serving to close communication between any given valve chamber 16 and the high vacuum conduit 14 aforesaid; while a valve 19 correspondingly controls communication between the same valve chamber and the low vacuum conduit 15. It will hence be seen that when the valve stem is up the respective group of pneumatics 10 is in communication with the high vacuum system; while when said stem is lowered the same pneumatics are in communication with the low vacuum system. Valve stem 17 is preferably tubular, as shown in Fig. 4, and such tube is plugged at 20 preferably at a point between valve 18 and the upper end of the stem. A comparatively minute perforation 21 is provided above the plug 20 and a second perforation 22 is provided near the end of the said stem. The stem is carried by brackets 23 and 24, as best shown in Fig. 1; such brackets being respectively secured to the upper and lower portions of the valve chest. A collar 25 secured to valve stem 17, limits the upward movement thereof by impinging against the underside of bracket 23, and the said collar has secured thereto the diaphragm 26, the periphery of which is made fast to the edges of an aperture 27 provided in the upper portion of the valve chest. A corresponding collar 28 and diaphragm 29 are positioned near the lower portion of the stem, and are correspondingly secured thereto; diaphragm 29 closing aperture 30 in the lower portion of the casing in corresponding fashion to the manner in which aperture 27 is closed by diaphragm 26. A spiral spring 31, the diameter of which tapers gradually toward its upper end, as shown in Fig.

1, bears against the lower surface of valve 19, the lower end of said spring being seated against the bottom of the valve chest. Spring 31 hence normally tends to maintain valve 19 against its seat, leaving valve chamber 16 in communication with the high vacuum conduit. Below the valve chest 13 are a series of pockets, in the lower portion of each of which is formed a diaphragmed chamber 32. Each of said pockets is closed by a diaphragm 33, and the space above said diaphragm is in communication with the atmosphere by reason of an aperture 34 in the side of said pocket. The valve stems 17 extend downwardly into said pockets and the lowermost extremity of each of said stems is respectively secured to one of said diaphragms 33. As the stem is hollow and as a small aperture 35 is provided approximately at the center thereof, it is obvious that when either a high or low vacuum has been produced, the diaphragm 33 will be held in depressed position, since the hollow stem opens into the chamber 32, therebelow and this action is sufficiently strong to overcome the tendency of spring 31 to retain stem 17 in its upward position. The diameters of diaphragms 26 and 29 are substantially equal to each other, and are also substantially equal to the diameters of the valves 18 and 19, as a result of which, in so far as the relative degrees of vacuum in the conduits 14 and 15 is concerned, the several valve stems will be uninfluenced thereby to any material degree, and hence each will respond only to the actions of its diaphragm 33 and spring 31. From the above, it will be seen that when air is admitted to diaphragmed chamber 32, spring 31 is allowed to perform its normal function of throwing the respective pneumatic into communication with the high vacuum conduit; whereas the moment that atmospheric communication is cut-off from said chamber 32, the air will be exhausted therefrom through the interior of stem 17, and the stem will be correspondingly lowered, throwing pneumatic 10 into communication with the low vacuum system. The construction of valves 18 and 19 is somewhat peculiar in that it will be observed that each of said valves is provided with a thin or shallow flange 35', and the cylindrical body of each of said valves is notched, as at 36 for the passage of air. As the said body 37 is somewhat deeper than the depth of the seat 38, which engages flange 35, the lowermost edge of the body 37 of the upper valve 18 will engage the edge 39 of its valve seat before the lower valve 19 has cleared its corresponding edge, and hence communication between the high and low vacuum conduits can only occur through the small notches 36, effectually preventing any serious impairment of the vacuum in the high

vacuum conduit; while at the same time invariably permitting that particular group of pneumatics 10 controlled by such valves 18 and 19 to exhaust in normal fashion; so that while the notes controlled by such pneumatics may not be accented, they will at least sound, should the valve 18 be at an intermediate position at the instant when such notes are to be sounded, since air will 10 seep through notches 36 from the pneumatics to be operated into both the high and low pressure conduits. The interior of the upper guide bracket 23 is preferably lined with chamois or the like, so as to afford a proper closure to the vent 22 when the stem 17 is in its lowermost position, and a light spring arm 40, which is secured to the interior of the high vacuum conduit, normally tends to close aperture 21 when the latter is in its elevated position by covering the same with the end 41 of said arm. Such end may be tipped with chamois, if desired, in order to afford a proper closure. A tube 42 connects the upper extremity of stem 17 with a nipple 43, which leads into a quite small, diaphragmed pocket 44; a series of such pockets being formed by boring holes in a bar 45 of wood or the like, which is positioned upon the bottom of the 25 roll box, as indicated in Fig. 1. A diaphragm 46 closes each of said pockets, said diaphragm having secured in the center thereof a small disk 47 of cardboard or the like, to which is hinged a light link, 48 30 which may also be of cardboard; said link being correspondingly hinged to a flap 49. Flaps 49 are preferably white, and a portion of such flaps is adapted to be exposed through a slot 50 which is formed in the front of a casing 51 which incloses the said flaps, diaphragms, and connecting parts. In the interior of each of diaphragmed 35 pockets 44 is a hair spring 52, which normally distends its corresponding diaphragm 46 and thereby holds the white flap 49 which is secured thereto up against the inner side of the slotted casing. When the valve stem 17, is in its uppermost position, the aperture 21 being closed, and the vent 22 being 40 opened, air is admitted to the pocket 44 and the spring is enabled to exercise its function in the manner above described; but when valve stem 17 is depressed aperture 22 is closed and aperture 21 correspondingly opened so that the minute quantity of air contained in the said pocket is exhausted 45 therefrom; as a result of which, that particular flap 49 is pulled back away from slot 50. As the interior of casing 51 is quite 50 dark, when flaps 49 are not so exposed through said slot, the slot appears black; and hence, an efficient means is provided for indicating which pneumatics are in communication with the high vacuum system.

55 Considering now the method of operat-

ing the stems 17 aforesaid, it will be seen that a series of tubes 53 connect diaphragmed chambers 32 with their respective nipples 54, upon the nippled cylinder 55. These nipples are preferably outwardly directed in staggered relationship as shown in Figs. 7 and 8, and have their inner ends substantially in alinement as shown by the apertures 56 in cylinder 55, into which said nipples are inserted. The staggering of the 70 nipples permits a closer assembling of the same, so that the diameter of cylinder 55 may be made as small as possible. In this instance, as the respective pneumatics have been grouped into groups of three, there will 75 be substantially thirty nipples 54. The interior of cylinder 55 is preferably lined with chamois or leather or some other suitable and durable material 57, such material being correspondingly apertured with a series 80 of holes corresponding to apertures 56 in cylinder 55. It is evident that when any one of these apertures in lining 57 is closed, the air will be immediately exhausted from corresponding chamber 32 through the stem 90 17 and aperture 35 to the exhaust, so that that particular valve stem 17 will be correspondingly depressed. In order to control the uncovering of these apertures, I have provided a cylinder 58 which may be of 95 pressed glass, or metal, or other suitable material. Cylinder 58 is carried upon a suitable spider 59, which may be integrally formed therewith, and the hub of which spider is secured to a spindle or shaft 60; 100 such shaft being axially disposed with respect to cylinder 55. Cylinder 58 actually constitutes a cylindrical valve, and it is provided with a series of three rectangular apertures 61, 62 and 63. As shown in Fig. 105 2, the said apertures are all substantially the same width, and the right hand edge of one is in alinement with the left hand edge of the next. The width of each of these apertures is of just sufficient size to uncover 110 one of the small ports in the lining 57 above described. As viewed in Fig. 2, the outermost side of aperture 63 is open, and adjoins a slot or recess 64, which is of substantially 115 the same depth as each of slots 61, 62 and 63, but the arcuate width thereof is considerably greater, so that when slot 64 is disposed opposite the apertures in the said lining 57, a number of the apertures in lining 57 will be uncovered instead of one, 120 such number in this instance, four. A correspondingly wider slot 65 adjoins slot 64 and is adapted to uncover seven of the ports aforesaid, while the outermost slotted or cut-away portion 66 is adapted to uncover 125 fifteen of the said ports. It will hence be observed that this outermost slot will permit the accenting of substantially one-half of the register of the instrument. If now the cylinder 58 be given a certain axial dis- 130

position, such for example as to oppose aperture 63 to the individual ports in the circular line of the same in lining 57; one after another of said ports may be uncovered by merely rotating said cylinder, thus permitting the notes of the piano or other instrument to be successively or chromatically selected in groups of three. I may here state that if it be desired to provide an individual stem 17 and corresponding parts for each note in the register, it is obvious that the same may be done without necessitating any material change in the arrangement of the parts of my device; but I find in practice that the arrangement of the notes in groups of three is satisfactory, owing to the fact that notes one whole tone apart occur comparatively infrequently in music; so that the arrangement of the notes in groups of three results in practically enabling the operator to select at will any desired note in a piece to accent the same. If now the slot 64 be disposed adjacent to the said ports any notes which come within the group of twelve notes so covered may, of course, be accented. In corresponding fashion when slot 65 is so positioned, the group of accentable notes at the disposition of the operator is correspondingly enlarged, and such group comprises a still greater number of notes when slot 66 is used. If now cylinder 58 be rotated, it is apparent that the group will not change substantially in number, but will be shifted up or down the register according to the direction of rotation of the said cylinder.

Let us now consider the means for controlling cylinder 58 by the action of which the desired results aforesaid are attained. The spindle 60 is revolvably mounted in brackets 67, 68, the positions of such brackets being diagrammatically indicated in Fig. 2. To the rear of cylinder 58 is a small pulley 69 which is keyed or otherwise properly secured to shaft 60. The helical spring 70, which is preferably of considerable length and quite flexible has one end 71 thereof secured to shaft 60 or to pulley 69, and the other end is correspondingly secured to bracket 68. This spring normally tends to push the shaft outwardly toward the front of the piano, and also normally tends to rotate cylinder 58 clockwise as viewed from the front. The spring therefore performs a double function, and serves to invariably return cylinder 58 to a predetermined and definite position when permitted so to do. A suitable chain or cord 72 has the end thereof secured to the periphery of pulley 69, and passing around the said pulley goes from thence over to a pivotally mounted segment 73. Segment 73 is pivoted to a pawl or stud 74 which is carried by a suitable bracket 75. I prefer to provide a sleeve 76 in said segment, such sleeve being made of metal and the segment of wood.

Upwardly extending from the face of segment 73 are two parallel lugs 77 through which extends a pin 78, said pin bearing pivotally mounted thereon a member 79, the upper face of which as shown in Fig. 2 carries a pin 79, to which is secured the end of a link 80. The other end of link 80 is in turn somewhat loosely pivoted to a pin 81 carried by the arm 82 of a bracket 83. Arm 82 is bifurcated at the end thereof for the reception of the end of said link and suitable leather or flannel washers 84 are provided upon the respective sides of the end of rod 80, permitting said rod to swing or oscillate laterally in all directions to some extent. The plurality of pivoted connections to the member 79 at the other end of said rod perform a similar function to accommodate the lateral play of said rod when the same is moved to and fro. Rod 80 is reciprocated by the movement of a shaft 85 which carries the bracket 83 thereon, shaft 85 being grooved as at 86 for engagement with a pin 87 carried by the said bracket. Groove 86 opens into an annular recess 88, which extends around shaft 85 and the walls of said groove, where it opens into said recess, are outwardly flared as at 89 so that when rod 85 is pushed inwardly, the pin 87 will be disengaged from slot 86 and will be free to move in recess 88; while the flaring walls 89 of the slot will facilitate the reengagement of the pin with the same when shaft 85 is retracted. The bracket 83 is prevented from moving longitudinally with said rod by a bracket 90 which engages the respective sides thereof. The bracket 90, which has been merely diagrammatically indicated in Fig. 2, in order to avoid confusion, carries the innermost end of rod 85 while the outer end of said rod is supported by a bracket 91; bracket 91 having a larger bore than the said shaft in order to accommodate a sleeve 92, which may have a force fit with said bracket. This sleeve is grooved at 93 in the manner illustrated in Fig. 6, so that a pin 94 carried by the said shaft will engage the said groove and force the shaft to rotate in a predetermined manner when said shaft is reciprocated. The outer end of shaft 85 carries a shaft bracket 95 suitably secured thereto, said bracket having pivoted thereupon a handle 96 which is provided with a pair of wing-like lugs 97, the face of which is flat for the most part but somewhat outwardly flared at the ends as shown. The outward movement of handle 96 may be limited by means of a set screw 98, carried by shaft bracket 95. The general arrangement of this portion of the device is substantially similar to that shown in my companion application, Serial No. 542,766, filed Feb. 8, 1910, and the appurtenances to the handle therein described are equally appli-

cable to this form of the device. The oscillation of lever 96 effects a corresponding rotation of shaft 85 and through the instrumentality of bracket 83 and arm 82, link 80, segment 78, chain or cord 72 and pulley 69, a corresponding movement of spindle or shaft 60. It will be observed that the movement, however, will be considerably magnified so that a relatively small lateral movement of lever 96 will effect a considerable rotation of cylinder 58. The flat face of the wings 97 is adapted to bear against a small roller 99, which is carried in the fork 100, which is provided intermediate the ends 15 of a lever 101. A lever 101 is pivoted to the under-side of the piano front at 102, and carries upon the free end thereof a pivoted finger 103 which is recessed at its free end 104 for the reception of the reduced end 20 105 of shaft or spindle 60. Stop pins 106 limit the lateral motion of finger 103, such members being merely provided to prevent lateral thrust upon shaft 60 when lever 101 is oscillated to translate said shaft. It is obvious therefore that when lever 96 is pressed inwardly about the pivotal axis indicated by the dotted line shown just back of the lugs 97 in Fig. 2, such lever being in operative position as shown in Figs. 1 30 and 2, translation of shaft 85 is prevented by reason of the engagement of pin 94 thereon with the arcuate portion of slot 93, while through the engagement of roller 99 with the flat surface afforded by wings 97, the cylinder 58 will be driven inwardly through the action of lever 101 upon the spindle 60, resulting in the compression of spring 70 and the shifting of various slots 61, 62, etc., into successive apposition with 35 the controlling ports in the lining of the nippled cylinder. We have hence a means of rotating cylinder 58 into any desired position and of also translating the same; as a result of which double action, it is obviously possible to accent any desired note or notes in the register, by merely manipulating a single lever. This lever is not dissimilar to that in my aforesaid application, as has been hereinbefore stated, although 40 the selective means herein set forth is quite different. I now present, however, means for not only controlling the accenting device manually, but for also controlling the same automatically, and one form of the mechanism which may be employed to this end will be now described.

When it is desired to no longer exercise manual control, the handle or lever 96 is rotated so that the pin 94 follows slot 93 45 down around through the arcuate portion permitting the shaft 85 to be translated under the piano front and owing to the upward trend of the inner end 107 of slot 93, the lever 96 will be rotated up closely 50 under the front of the piano. Bracket 83 bearing arm 82 will be disengaged from shaft 85, and the inner-most end 108 of shaft 85 will impinge against the extremity 109 of a lever 110. Said lever is pivotally mounted at 111 upon an arm carried by 55 bracket 90, and is normally restrained into the position shown in Fig. 1 by the action of a spring 112, one end of which is secured to the lever 110, and the other, to the said arm of bracket 90. When lever 110 is actuated 60 through the action of shaft 85, the link 113 which is secured to the other end of said lever, pushes a slide valve 114 into valve box 115, and thereby throws an exhaust pipe 116 into communication with pipes 65 117 and 118, air then passing freely through ports 115' of the valve box and aperture 116' of the valve. The exhaust pipe 116 is connected to the high vacuum system, and it is evident that it is only in communication with said pipes 117 and 118 when shaft 65 is in its innermost position owing to the action of spring 112. Of course any suitable valve might be operated by the action of shaft 85; the broad idea being that when 70 the manually controlled accenting means are thrown out of use, automatically operating devices are thereby thrown into action through the displacement of one of the parts aforesaid. Pipes 117 and 118 respectively 75 communicate with exhaust chambers 119, such chambers being formed in blocks 120, which are adapted to be secured by suitable brackets 121 to the under-side of the piano front. The entire interior of each of these 80 blocks is substantially hollow to form chambers 119, one of said blocks being shown in section at the right hand side of Fig. 3. Pipe 118 is there shown as communicating with said chamber; the chamber being also 85 provided with two nipples 121, 122, which extend downwardly therefrom. Block 120 is preferably of wood, and is faced upon either side thereof with metallic plates 123 and 124. A washer or liner of leather 125 is provided between plate 123 and block 120 and correspondingly between plate 124 and said block. The outer portion of block 120 is substantially similar in construction to that of the block 126 shown in section in 90 Fig. 5, and such construction may be here described. The end of the wooden block 126 is recessed as at 127 to form a cup-shaped depression. This depression is covered by a block 128 which has a corresponding recess 129 therein; the edges of blocks 126 and 128, clamping between them the diaphragm 129; said diaphragm being provided with a plurality of apertures 130 as shown in Fig. 5.

To the outer side of diaphragm 129 is secured a disk 131 of suitable light material such for instance as papier mâché; and the said disk has secured thereto a stem 132, which projects outwardly therefrom and 130

carries upon its outer end a smaller disk 133. Disk 133 is secured to the inner face of a diaphragm 134; such diaphragm being clamped around its peripheral portions between block 128 and a plate 135, which is secured to the extremity of the device. Plate 135 carries thereon a suitable nipple for engagement with a tube 136. The inner side of plate 135 is notched at one portion thereof near its periphery, as at 137; and a corresponding notch or recess is provided in the opposing face of block 128, as at 138. The diaphragm 134 is seated firmly into recess 138 and has an aperture formed therein at this point which affords communication with the space between the somewhat loose diaphragm 134 and cover plate 135, and the passage 140 via the bleed hole 139 which leads through a portion of block 128 and communicates with the exhaust passage 140, which leads from the chamber 141 formed between the diaphragm 134 and the diaphragm 129. The disk 131 serves as a valve to close the port between chamber 127 and 141; and the air being exhausted normally from both sides of diaphragm 134, positions valve 131 against its seat quite firmly by reason of the atmospheric pressure in chamber 127. When, however, air is admitted through tube 136, the diaphragm 134 will be bellied out, and by reason of its comparatively large area will open valve 131 and permit air to be exhausted from port 142, which is in communication with chamber 127. Port 142, it may be here noted, leads into a pneumatic, the bellows of which are shown at 143.

Referring now to Fig. 3, it will be seen that means have been shown whereby the pneumatic 144 communicates with the chamber 119, through the conduit 145 in similar fashion to that in which pneumatic 143 communicates with conduit 140. A nipple 140 leading from conduit 140, correspondingly communicates with the nipple 121 leading to chamber 119 by means of a flexible tube 146 shown in dotted lines in Fig. 2, and in full lines to the left of Fig. 3. A block 147 similarly provides means for throwing a pneumatic 148 into communication with chamber 119, through the instrumentality of a similar tube 149. The pneumatics 144, 143 and 148, have a relative displacement proportional respectively to units 1, 2 and 3; that is, the movement which pneumatic 143 is adapted to effect is twice that of pneumatic 144, and pneumatic 148 is correspondingly adapted to effectuate a movement equal to three times that causable by a full movement of pneumatic 144. As all of the blocks and pneumatics are secured to each other in succession, in the manner shown, it is apparent that when the air is exhausted from one of the three a corresponding rotation will be effected of the

plate or member 150 which is secured to the farthest side of pneumatic 148. Plate 150 carries upon the upper portion thereof a laterally extending lug 151, from which lug a pin 152 extends upwardly a sufficient distance to engage a bent rod 153 which is secured by screws, or in any other suitable manner, to segment 73' shown upon the right hand side of Fig. 2. Where the segment is of larger radius as shown at 73 upon the left hand side, pin 152 engages the end of a slot 154 on the under side of said segment; the action, however, in both cases is substantially the same, it being merely desired that each pin 152 shall have no fixed connection with its respective segment, in order that the pneumatics may not be operated by the movement of lever 96. The rod 153 is somewhat L-shaped, the long arm thereof being curved into arcuate form and the extremity of such rod being provided with a cup-shaped leather washer 155, which is secured to the end thereof by means of a metallic backing washer and screw in the usual manner in which such parts are assembled in dash pots. A similar construction is shown at the left hand side of Fig. 2; rod 153' being there shown as engaging an arcuate tube 156, the innermost end 157 whereof is closed. Rod 153 extends into a similar tube in corresponding fashion. The function of this part of the apparatus is to operate as a dashpot so that the parts may not return too quickly to their normal positions under the influence of spring 70; the dashpots being in each case adjusted to the end that such movement may be rapid, but free from jolt.

The apparatus shown on the right and left hand sides of Fig. 2 are substantially the same except for the difference in the size of segments employed and the particular duty or function of such segments; and thus a description of one will suffice for both. The arcuate rod 153' is adapted to be gripped between the jaws 158 and 159 of the brake mechanism shown in Fig. 15; said jaws being pivoted together at 160, and such pivot being supported by means of a suitable bracket (not shown) which may be secured to the under side of the piano front. Jaw 158 is integrally united with an arm 161; and jaw 159 is correspondingly joined to an arm 162; so that when the said arms 161 and 162 are spread apart, the jaws clamp together upon rod 153'. Such action is effected by means of a slotted block 163, the slots whereof form an interior wedge-shaped portion 164, which engages the ends of arms 161-162. Block 163 is normally driven into engagement with the said arms, as above described, through the action of a spring 165, which bears against the said block and a bracket 166, through which passes a rod 167, which carries the said

block 163. Bracket 166 may be secured to the under side of the piano front, as may be also a suitable pneumatic 168, which pneumatic is adapted to retract block 163 against the action of spring 165, and when such retraction occurs, the lugs 169 and 170 of block 163, respectively engage arms 161 and 162 forcing the jaws 158 and 159 open. The evident result of this braking action is to retain the rod 153 in any given position in which it may happen to be when the brake jaws seize it. As shown in Fig. 2, the pneumatics above described are not adapted for operation since the exhaust is shut off therefrom; and hence, the respective groups of pneumatics are distended to the limits of their movements, being opened out accordion fashion under the action of springs 171, which respectively engage the plates 150, the other ends of said springs being secured to the piano casing. When the manual operating means are disengaged, the pins 152 will come into engagement with the respective engaging parts, namely, in one case the rod 153, and in the other, the outer end of slot 154, so that any action of the said pneumatics in a given group of the same will result in a corresponding actuation of the proper segment. When the pneumatics of the group upon the left hand side are operated, they rotate the shaft 60, and hence the cylinder 58; while when those upon the right hand side are actuated, they move a link 172, one end of which is pivotally connected to segment 73', and the other end of which is connected to a bell-crank 173 which is pivoted at 174 to the under side of the piano casing. The remaining arm of said bell-crank is correspondingly connected to a link 175 which in turn is pivoted at 176 to the lever 101, and hence movement of segment 73' results in translation of the cylinder 58.

The pneumatics 144, 143 and 148, are respectively controlled through the admission of air through tubes 177, 136, hereinbefore referred to, and tube 178, there being of course a right hand group of three such tubes, and a corresponding left hand group. The left hand group communicates respectively with apertures 179, 180 and 181 which are located at the left hand extremity of the tracker 182. These apertures are preferably positioned in alinement and are located just beyond the end of the line of apertures 183, in the tracker, which serve to control the note sounding pneumatics. A corresponding group of three apertures or ports is provided at the other end of the tracker, and such ports communicate through their respective tubes with the right hand group of expression-control pneumatics. A section of a sheet of perforated music is indicated at 184 in Fig. 3, and in 88 note music there is usually a certain space along either edge

thereof which is free from perforations; the overall length of the group of ports 183 being somewhat less, approximately one inch and a half, than the width of the paper roll. There is hence ample space for the provision of additional apertures 185 along the respective edges, such apertures being adapted to uncover ports 179, 180 and 181, as desired. Should, for example, a port 179 be uncovered by an aperture passing thereover, a corresponding pneumatic 144 will be actuated. Similarly if port 180 be uncovered, pneumatic 143 will act, and in similar fashion pneumatic 148 is controlled from port 181; the ports upon the left hand side of the tracker controlling the left hand group of pneumatics, and the apertures on the right hand side controlling the right hand group of pneumatics. As the said pneumatics are all secured to each other it becomes possible to move plate 150 of either one of the groups into any one of seven positions; since when all of the ports are closed the plate will be in the position shown in Fig. 2. If port 179 be opened and the other two remain closed, the plate 150 will angularly advance one step. Similarly, if port 180 be uncovered, and ports 179 and 181 remain closed, it will advance two steps, i.e., twice the advance previously accomplished. In like manner if port 181 be uncovered, 179 and 180 remaining closed, the plate will advance three steps. Now if ports 178 and 181 be simultaneously uncovered, the plate will advance through four steps. If 180 and 181 be uncovered, it will move through five steps, and finally if all three ports be uncovered at one time, it will be moved through its entire travel, which is equivalent to six steps. It therefore follows that the cylinder 58 may be rotated into any one of seven positions, and in like manner, it may be correspondingly translated into any one of seven positions by means of the right hand pneumatics.

As has hereinbefore been stated holes 61, 62 and 63 dominate ordinarily one port in the valve cylinder at one time, and the holes 64, 65 and 66 correspondingly larger numbers of ports. As the cylinder is adapted to be moved axially into any one of seven positions, the first position will normally place apertures 61 in alinement with the ports, the second, aperture 63; the third, aperture 64; the fourth, slot 65; the sixth, slot 66; and the seventh will uncover all of the ports, thereby placing all of the note sounding pneumatics in communication with the high vacuum system. If now, the steps in rotation be so arranged that a single step of the pneumatics in the left hand group will rotate a given aperture as for example 62, in cylinder 58, past three apertures in the line 57 of cylinder 55, and correspondingly advance three more for each successive step.

of its travel, it is evident that the central note of the group of three controlled by each of said lining apertures, will be spaced ten notes distant from the central note of the group dominated by the next step. In other words, the notes can be accented in groups of three and such groups can be moved at will up or down the register skipping six intermediate notes at a time. As now the edges of apertures 61, 62 and 63, are in alinement as hereinbefore described, if aperture 62 controls the traveling group in question, it is evident that if the cylinder be not rotated, but be translated inwardly or outwardly one step, the intervening groups of three notes each will also be controlled. In this way through the coöperation of the right and left hand sets of pneumatics it becomes possible to practically select an individual note on the piano anywhere within the range wherein accenting is likely to be desired, simply by the operation of uncovering one or more of the group of six additional ports provided in the tracker. In other words, the alteration of the density of air in such ports effects the actuation of the controlling elements of the expression device, the constituent ports of such group of six ports being adapted for permutations and combinations with each other, whereby the said elements may be properly selected. In order to save air and consequent work upon the part of the performer of the instrument, assuming the same to be operated by pedals, I provide the brake mechanism hereinbefore described. It will be observed that immediately above ports 179, 180 and 181, are three ports 186, 187 and 188. These ports may be made continuous if desired, that is, all in one, but in order to prevent crinkling of the paper of roll 184, it is preferable that they be made as individual ports, such ports, however, opening into a common tube 189, and such tube controlling the brake pneumatic 168. For simplicity of illustration, the right hand brake pneumatic and its corresponding tube 189 have been omitted in Figs. 2 and 3, but it will be understood that, as has hereinbefore been stated, the arrangement of these particular ports is substantially the same upon the right and left hand sides of the selecting mechanism. It follows therefore that as any given aperture 185 approaches its corresponding port 179, 180, or 181, it first uncovers a brake port 186, 187, or 188, and as the space between ports 186 and 179, and in corresponding fashion the remaining ports of the group, is very small, the bridge being preferably merely of sufficient width to prevent air leaking through under the paper roll, the brake pressure will be removed from rod 153 or 153, just an instant before the respective group of pneumatics is operated; and apertures 185 may hence be quite short, since the

brake will be set again immediately after the pneumatics have assumed their proper positions, locking the same in such positions, and the exhaust being thereafter cut-off from said pneumatics; the tendency to return to their initial positions shown in Fig. 2 under the action of spring 171 being overcome through the friction of the brake jaws. The quantity of air consumed by my selective mechanism is hence very small, and this I regard as a most valuable feature, and one which I believe is broadly new and novel.

We may now consider the operation of the mechanism for controlling the relative intensities of vacuum in conduits 14 and 15. Conduit 14 communicates with a bellows 200 by means of a port 201 conveniently located in a base block 202, said port being in communication with a large diametered tube 203. Correspondingly conduit 15 communicates by means of tube 204 and a port 205 in said block 202, with a bellows 206. It will be understood of course that suitable reservoir or auxiliary vacuum chambers of the usual description should be inserted into the system where needed, together with the usual check valves, indicated by dotted lines at 203. The pair of bellows 200 and 206 shown in Fig. 1 are positioned toward the right hand end of the piano in the interior thereof and a corresponding set of bellows is provided in the other end, and I prefer to provide in like manner two sets of tubes 203 and 204, so that the conduits 14 and 15 are in communication with their respective bellows from the respective ends of said conduits. The blocks 202 are rigidly supported in any suitable manner in the interior of the piano casing, and substantially at the center of said casing I provide a U-shaped bracket 207 one-half of which is shown in Fig. 1. A shaft 208 extends between the upper ends of the arms of the said bracket; and such shaft, which is preferably fixed, has pivotally mounted thereon two bell-cranks 209. Considering now the action of one of these cranks, the one shown in Fig. 1, the lower end of one arm 210 on said crank, is pivotally connected to a link 211, which in turn is hinged to the free end of a pedal 212. This pedal is pivotally mounted at 213 upon a frame 214, which frame is of sufficient width to properly support both the right and left hand pedals. The frame 214 is pivoted to a bracket 215, the base of which extends along the bottom of the piano casing; said bracket being also somewhat U-shaped. Frame 214 is preferably a casting and is quite rigid; the sides thereof being connected by cross members or bars 215 and 216. This frame and the pedals carried thereby are adapted to be rotated around into the interior of the piano casing in the manner shown in Fig. 12, so that the usual slide may cover the aperture in the front of the piano 130

through which they have passed. The bellows 200 and 206 are each substantially of the usual construction, being each provided with the usual spring 217, which normally tends to maintain its bellows closed. The upper arm 209 of the bell-crank is connected to an operating arm of bellows 206 by a link 218, and the lower arm of said crank is correspondingly connected by link 219 to the operating arm 220 of bellows 200. As these bellows normally tend to remain closed under the action of their respective springs, it follows that the bell-crank in question normally tends to return to the position shown in Fig. 1, which obviously throws the pedal 212 to its outermost position. As stated, the pedal mechanism is in duplicate, there being of course two sets of links 211, 218 and 219. The points of connection of the several parts aforesaid bear such relationship to each other that as the pedals descend, toggle actions occur, link 218 and the upper arm of the bell-crank forming one toggle; and link 219 and the lower arm of said crank forming the other toggle; this latter toggle being straight when the parts are positioned as shown in Fig. 1, and broken when the pedal 212 is depressed. As the result of this, and my peculiar disposition of pivotal connections, as the pedal 212 is moved downward through the first quarter of its stroke, the low pressure bellows 206 is distended practically to its limit; its operating arm having but little farther distance to travel before it reaches the end of its movement. While this has been taking place, bellows 200 has been distended through about one-third of its movement. The above action is diagrammatically indicated in Fig. 13, where the initial position of the point of connection between link 219 and arm 220 of the bellows is indicated at 221, its final position being indicated at 222, and its position when approximately one-third of its travel has been accomplished, being indicated at 223. Correspondingly the point of connection to bellows 206 at the beginning of its stroke is indicated at 224, and its position after the pedal has descended one-quarter of its stroke is shown at 225, the distance between points 224 and 225 being very nearly the entire travel of such point, the limit of movement being indicated at 226. In corresponding fashion, when one-half of the stroke of the pedal has been accomplished, the high vacuum bellows has distended about two-thirds of the full amount of which it is capable, while the low vacuum bellows 206 has not materially altered its volume.

At the end of the third quarter of the stroke of the pedal, the high vacuum bellows has reached approximately three-quarters of its possible distention, while the low vacuum bellows 206 has actually begun to retrogress, the vacuum therein being very

slightly reduced. Finally in the fourth-quarter of the stroke of the pedal, the high vacuum bellows is distended to its fullest extent, while the low vacuum has been reduced approximately thirty per cent. As a result of this action, it becomes possible to nicely adjust the degree of vacuum in the respective conduits, since if the pedals be operated only through the first quarter of their stroke, the conduit 15 may actually have the higher vacuum, while by pedaling through the half stroke, the degree of vacuum in conduit 14 is correspondingly increased, and finally by pushing the pedal down sharply through three-quarters of its throw, or if need be its entire stroke, the degree of the high vacuum may be made relatively very high as compared to that of the low vacuum. This permits one or more notes which may have been selected by either the manually controlled mechanism or the automatic devices to be accented with great vigor, a feature which has been hitherto substantially unaccomplishable. My novel vacuum producing means and selective mechanisms hence coöperate to afford practically absolute control of the register, and it becomes possible thereby to either manually or automatically select any given note or notes in the register and to accent the same with any desired degree of intensity, as compared to the remaining notes of a chord. Thus a chord may consist of ten notes, and it may be desired to accent one, two, three or more of said notes, and such notes may be accented either at the will of the performer or the mechanism will automatically select them without the performer, who then has means at his disposal for making the notes stand out from the back ground formed by the remaining notes of the chord as sharply as he may desire. Furthermore, such degree of accentuation can be varied through as great an extent as if the keys of the instrument had actually been played by hand. This I believe marks a most decided advance over any expression device which has heretofore been produced, inasmuch as in devices for this purpose as heretofore constructed, the notes to be accented have been accented with a substantially invariable proportional degree of intensity of tone over the remaining notes simultaneously struck. For example, if a chord of six notes be struck and one note be accented, the force with which such note will be sounded will be, let us say, twice that of any of the remaining tones; but it cannot be made three times or four times such amount at will, as can be done by means of mechanism constructed in accordance with my invention.

It is obvious of course that my invention readily adapts itself to extension. For ex-

ample, if the three control pneumatics on each side be arranged to cover units 1, 2 and 4 instead of 1, 2 and 3, as above described, the summation of such pneumatics in groups of one or more will give as high as seven steps instead of six, and this together with the initial position affords a total of eight distinct positions into which the cylinder 58 may be rotated and eight into which it may be translated. If now the note sounding pneumatics be arranged in groups of two instead of in groups of three, and the step of rotation advance eight notes at a time, instead of ten, as above described, and if the cylinder 58 be correspondingly apertured with four single-port apertures instead of three, the entire range of the eighty-eight notes of a piano can be dominated in groups of two, and the chromatically disposable groups may be provided for respectively embracing, let us say six, nine, twelve, fifteen, twenty-one, thirty-three and forty-five notes, and still permit of the entire register being operated from the high vacuum system. On the other hand, instead of disposing the acceptable notes in single groups of six, nine, twelve, etc., as just described, octaves may be accented in addition to the single notes, such octaves being dominated by pairs of apertures properly spaced apart, in lieu of some of the wide slots. Using four pneumatics on a side we may therefore dominate the whole register in groups of two, have in addition chromatically disposable groups of say sixteen, thirty and forty-four notes respectively and by devoting four of the translation movements or steps to the disposition of the octave apertures just described, octaves may be separately accented anywhere on the piano, intermediate notes between the octave spaced notes not being accented. A valve cylinder of this description has been shown in Fig. 17, the single-port apertures being designated 227, the octave spaced ports 228, the sixteen note slot 229 and the corresponding thirty and forty-four note slots being merged into a sloping sided aperture, the oblique walls of which are shown at 230, the number of thirty ports, for example being uncovered when the cylinder has been translated to a position where the line of ports coincides with the line indicated at 231. This sloping sided arrangement of slot possesses certain advantages over the slot formation shown in Fig. 2, especially when the device is being manually operated, since then the chromatic groups may comprise any number of notes instead of certain predetermined numbers. If five control pneumatics be used upon each side, namely of units 1, 2, 3, 5 and 7, the control automatically exercisable over the instrument is practically perfect, as the summation limit is

in this case, 18, which with the initial position, or position in which no pneumatics are or have been in use, makes the total of 19 steps of translation and correspondingly 19 of rotation.

70

I wish to state here that it is not essential that one valve member be stationary, the other being both translatable and rotatable; since in some cases it may be desirable to rotate one member and translate the other; 75 and in fact rotation of a given member may be dispensed with and a second translation movement substituted therefor.

Having now disclosed the particular construction of the above embodiments of my invention, what I desire to particularly point out is the results which may be obtained by the use thereof. In the first place, by varying the relative degrees of vacuum in two independent systems, throwing such systems either at will or automatically into communication with the exhaust from note sounding pneumatics, I am enabled to accent any desired note or group of notes in a given chord, in any desired amount as compared with the remaining notes of such chord; and this without altering the timbre of any of the notes struck. It has been customary to modulate the intensity of tone in pianos by employing a felt strip or curtain which is made capable of being depressed and interposed between the hammers and the strings. The use of such a curtain produces a peculiar tangy quality in the notes struck and the timbre is materially altered. 95 When this device has not been employed it has been customary, particularly in the player piano art, to employ some device for lifting forward the hammer rest rail, or a section thereof, or the hammers themselves, 100 so that such hammers traverse a considerable less arc when actuated, and thereby produce softer tones. This expedient is, however, also objectionable, although probably not so much so as the other, in that the tone action is impaired and the timbre materially changed. This may be clearly demonstrated by still further shortening the stroke of the hammers, when even to the most unpractised ear, the thud-like quality 110 of the tone so produced will become apparent. By permitting the hammers to traverse the entire length of their stroke and merely altering the intensity of the blow delivered to them by the pneumatic, it becomes possible to maintain the timbre unimpaired while altering the weight or intensity of the tone.

115

120

125

My invention permits of notes being accented individually, picking out one note at the time no matter where it may occur, or a group of notes may be similarly accented, and that to any extent desired. The operator is enabled to effect this result manually, when he so wishes, by manipulating 130

a single lever or handle, preferably by the left hand, and when he desires to allow every tone struck to stand out in equal degree, it is merely necessary to press inward 5 upon said handle to the full extent of the throw.

My companion application sets forth means for operating a loud pedal pneumatic from said handle, or such pedal may 10 be operated from the usual lever or button, or it may be operated by proper perforations in the rolls, adapted for coöperation with a port in the tracker which may control the loud pedal pneumatic through the 15 usual valved appliances. My invention enables a quite inexperienced performer to play a piece of music with proper expression.

In the arrangement of parts as herein set 20 forth, the accented notes may be in number approximately one half of the whole number for which the player is adapted. Thus if an eighty-eight note player be used, the device may be made to accent forty-five notes 25 consecutively disposed anywhere along the keyboard.

By increasing the controlling diaphragms from thirty to eighty-eight in number and correspondingly increasing the number of 30 coöperating parts, where necessary, it is possible to compass the entire register individually instead of in groups of three. Further the configuration of the slotted valve controlling cylinder and the number of operating pneumatics therefor may be altered 35 to attain any group arrangement desired. I find however that the device as shown affords sufficient control for all practical purposes and having relatively but few and inexpensive parts is not costly of manufacture.

In certain of the appended claims I have sought to broadly set forth the novel construction employed to attain the varied control over the note sounding parts, whereby 45 not alone may they be accented substantially *scritam*; but a number of notes may be accented, practically wherever desired, and this number may be widely varied.

In the particular construction herein described, this is largely due to the manner in which the cylinder 58 may be moved. It is obviously rotatable about its longitudinal axis and, further, is mounted for movement of translation in that it may be shifted 55 bodily non-rotarily, as it happens in this particular case, in the direction of said axis. These movements may be combined so that a screw-like movement is imparted to the cylinder; this movement being either right 60 or left hand as desired.

I do not wish to be limited however to a construction such as that shown in the drawing wherein one and the same part has both rotary and translatory movements imparted

to it; nor indeed to these particular movements, given by way of exemplification, so that I have described the relative movements which take place between the exemplified parts in question, *i. e.* the inner cylinder 58 and outer cylinder 55, as movements in 65 diverse ways or directions.

I do not regard a part which merely moves back and forth in a straight line as being moved in diverse directions, since the word—diverse—implies being essentially dissimilar, and simple reciprocation in one line does not involve essentially dissimilar movements or directions of movement.

What I claim, is:

1. In an automatic musical instrument, a plurality of note sounding parts, force applying elements coöperating with said parts, the intensity of the force which said elements are capable of exerting being variable, devices for varying said intensity of force, to permit solo or thematic effects to be produced, and automatically operating means for controlling said devices, said means comprising a ported member and a port controlling member, one of said members being movable in one direction and one of said members being movable in a direction diverse to that just referred to, and means for effecting said movements.

2. In a musical instrument, a plurality of note sounding parts, force applying elements coöperating with said parts, the intensity of force which said elements are capable of exerting being variable, devices for varying said intensity of force, to permit solo and thematic effects to be produced, automatically operating means for controlling said devices, automatic indicating means for indicating the notes selected for accentuation by said operating means, and connections 105 between said two means for actuating said indicating means in correspondence with said means for controlling said devices.

3. In a musical instrument, a plurality of note sounding parts, force applying elements 110 coöperating with said parts, the intensity of force which said elements are capable of exerting being variable, devices for varying said intensity of force, to permit solo and thematic effects to be produced, automatically operating means for controlling said devices, automatic indicating means for indicating the notes selected for accentuation, connections between said two means for actuating said indicating means in correspondence with said means for controlling said devices, a manually controlled part adapted to co-act with portions of said automatically operating means for manually 115 controlling accentuation when desired, said connections between said means being operative for both the automatic and manual control of accentuation.

4. In a musical instrument, a plurality of note sounding parts, force applying elements coöperating with said parts, the intensity of force which said elements are capable of exerting being variable, devices for varying said intensity of force, to permit solo and thematic effects to be produced, and means for controlling said devices, said means comprising a member the disposition 10 of which determines the notes selected for accentuation, means co-acting with said member for selecting said notes, a group of co-acting, independently controlled instrumentalities for positioning said member in 15 any one of a plurality of positions, and a second group of co-acting, independently controlled instrumentalities for positioning said member in any one of a plurality of positions substantially different from the positions above referred to.
5. In a musical instrument, a plurality of note sounding parts, force applying elements coöperating with said parts, the intensity of force which said elements are capable of exerting being variable, pneumatic devices for varying said intensity of force, to permit solo and thematic effects to be produced, and selective mechanism for controlling said devices comprising a ported member 25 adapted for coöperation with a perforated roll, said ported member having a group of ports corresponding to the number of force applying elements used and having also auxiliary ports the number of which is relatively small as compared to said group 30 of ports, a member, a plurality of co-acting pneumatics controlled by the auxiliary ports aforesaid, said pneumatics being in two groups and each group adapted to act independently of the other, said governing member being in turn controlled by said pneumatics.
6. In musical instruments, a series of note sounding parts, actuating means for said parts, and an expression device for controlling the accentuation of notes, said device comprising a rotatable and translatable member, and mechanism for rotating and translating such member.
7. In an expression device for automatic and semi-automatic instruments, accenting means comprising a series of movable elements, a selective appliance coöperating therewith, said appliance having means for effecting a sequential displacement of elements in said series, means for varying the number of said elements simultaneously displaced, and mechanism for controlling the aforesaid two means of said appliances, said mechanism having two parts, one of which controls one of said means and the other of which controls the other of said means, said parts being separately as well as jointly movable, a separate movement of only one

of said parts substantially affecting only the disposition of the means controlled by such part.

8. In musical instruments, a series of note sounding parts actuating means for said parts, and an expression device for controlling the accentuation of notes, said device comprising two co-acting members, one of said members being rotatable, one of said members being translatable mounted, and mechanism for rotating said rotatable member and for imparting a movement of translation to said translatable mounted member.

9. In musical instruments, a series of note sounding parts, actuating means for said parts, and an expression device for controlling the accentuation of notes, comprising a rotatable and translatable member, and mechanism for rotating and translating such member, said mechanism comprising elements whereby the member may be controlled either manually or automatically.

10. In musical instruments, a series of note sounding parts, actuating means for said parts, and an expression device for controlling the accentuation of notes, comprising a member having an aperture therein movable both longitudinally and laterally into apposition with any portion of a predetermined area, and means for shifting said aperture both longitudinally of said area and laterally with respect to the line of such longitudinal movement.

11. In musical instruments, a series of note sounding parts, actuating means for said parts, and an expression device for controlling the accentuation of notes, comprising a valve member and a coöperating ported member, one of said members being movable with respect to the other in a plurality of different and divergent directions, and mechanism for moving said member in said different and divergent directions.

12. In musical instruments, a series of note sounding parts, actuating means for such parts, and an expression device comprising a ported structure having a plurality of ports therein, an element having an aperture therein adapted to co-act with said ports, said structure and element being mounted for relative movement therebetween in at least four different ways or directions to permit said aperture to be variously positioned with respect to said ports, means for effecting said relative movement whereby to variously position said aperture with respect to said ports, and means whereby the relative disposition of said aperture with respect to said ports controls the relative tone values producible by said note sounding parts.

13. In musical instruments, an expression device comprising a member mounted for oscillatory movement, a member mounted

- for rotation and also for translation in the direction of its axis of rotation, and means mounted upon the instrument for effecting the engagement and disengagement of said members.
14. In musical instruments, the combination of an expression device having means for selecting for accentuation various numbers of notes at one time, a tracker, music roll holding means, devices for indicating the relative positions of notes which are accented, pneumatic means for operating said devices, and connections between said pneumatic means and said selecting means.
15. A pneumatically operated musical instrument comprising material disposed to form a series of cells, a plurality of conduits having ported connections with said cells, and pneumatically operated mechanism for placing variable numbers of said cells into and out of communication with one of said conduits, said mechanism comprising a port controlling device and means for mounting said device for movement in a plurality of diverse ways.
16. In pneumatically operated musical instruments having tone sounding mechanisms controlled by a perforated music roll, an expression device comprising a series of valve parts, and a controlling device therefor having as elements thereof a ported structure and a single co-operating member, both of which are distinct from said perforated roll and one of which parts is movable with respect to the other, a determinably variable number of said valve parts being displaced and set apart from the remaining parts of said series in accordance with such movement, means controlled by said movable part for displacing variable numbers of said valve parts in manner aforesaid, said variable number being of any desired size and being displaced whenever desired in said series in accordance with the relative disposition of said member to said structure, and means for automatically effecting the desired relative disposition of said member to said structure.
17. A pneumatically operated musical instrument comprising material arranged to form a series of cells, a plurality of conduits having ported connections with said cells, and pneumatically operated mechanism for placing variable numbers of said cells into and out of communication with one of said conduits, said mechanism including a port controlling device movable in a plurality of diverse ways and means for moving said device in said diverse ways.
18. In musical instruments, means for sounding a chord the tone values of the respective notes of which are of varying intensity, comprising note sounding devices, operating means therefor, and means for regulating the intensity of action of said note sounding devices, said last mentioned means including material disposed to form air ports, a plurality of controlling members for said air ports, and automatic mechanism for displacing said members with respect to one another in a plurality of diverse directions.
19. In musical instruments, means for sounding a chord the tone values of the respective notes of which are of varying intensity, comprising note sounding devices, operating means therefor, and means for regulating the intensity of action of said note sounding devices, said last mentioned means involving a plurality of co-operating members, and means for displacing one of said members with respect to another of the same, one of said members being provided with a series of ports and another of said members having means for opening an intermediate number of said ports in said series while ports upon both sides of said intermediate number are closed, said means for regulating the intensity of action of said note sounding devices further comprising provisions for automatically varying said intermediate number of ports.
20. In musical instruments, means for sounding a chord the tone values of the respective notes of which are of varying intensity, comprising note sounding devices, operating means therefor, and means for regulating the intensity of action of said note sounding devices, said last mentioned means including a plurality of co-operating members, means for displacing one of said members with respect to another of the same, one of said members being provided with a series of ports and another of said members having means for opening an intermediate number of said ports in said series while ports upon both sides of said intermediate number are closed, and unitary means for varying said intermediate number while maintaining the substantially central port of such intermediate number in its previous position with respect to the remaining ports of the series when said last mentioned means alone is actuated.
21. In musical instruments, the combination of tone sounding devices with an expression device including a series of valves, automatic valve controlling mechanism comprising a structure positionable for selecting for actuation, within predetermined limits, an intermediate number of said valves, said number being variable as desired, said variable number to include as an element thereof any desired or indicated valve in said series of valves, said mechanism further including automatic means for moving said structure, and means for actuating the selected valves.
22. In musical instruments, a plurality of note sounding parts, operating mechanism therefor, tone intensifying means comprising

ing elements coöperating with said mechanism and controlling the same in accordance with the relative positions of said elements, automatic mechanism for positioning at least one of said elements in any one of a number of positions, said number being greater than two, said automatic mechanism including a perforated roll and a tracker adapted for engagement with said roll, auxiliary and manually operable means for positioning at least one of said elements in any one of a number of positions, said number also being greater than two, when desired, and means for disconnecting said automatic mechanism by an actuation of a manually controlled operating part of said auxiliary means.

23. In musical instruments, note sounding devices, pneumatic appliances for actuating said devices, and air exhausting means for operating said appliances, said means comprising a plurality of independent vacuum systems, each having its own air rarefying means, a pedal, and connections between said pedal and parts of said air rarefying means comprising levers, so pivoted that portions of the stroke of said pedal will effect a greater movement of one air rarefying means than that of another of said means, while other portions of said stroke will effect a change in the proportion between the movements aforesaid, and selective mechanism for placing said pneumatic appliances in communication with one or another of said vacuum systems.

24. In musical instruments, note sounding devices, pneumatic appliances for actuating said devices, and air exhausting means for operating said appliances, said means comprising a plurality of independent vacuum systems, each having its own air rarefying means, a pedal, and mechanism whereby the movement of said pedal will effect the rarefaction of air in the respective systems aforesaid, in differing degrees, and selective mechanism for placing said pneumatic appliances in communication with one or another of said vacuum systems.

25. In musical instruments, note sounding devices, pneumatic appliances for actuating said devices, and air exhausting means for operating said appliances, said means comprising a plurality of independent vacuum systems, each having its own air rarefying means, a pedal, and toggle acting mechanism whereby the movement of said pedal will effect the rarefaction of air in the respective systems aforesaid, in differing degrees, and selective mechanism for placing said pneumatic appliances in communication with one or another of said vacuum systems.

26. In a pneumatically operated musical instrument, a series of note sounding devices, a series of appliances for directly actuating said devices, an expression device

comprising a series of movable elements substantially corresponding to said series of note sounding devices, selectively acting means for effecting the movement of certain of said elements whereby the corresponding notes may be accented, foot pedals for actuating said instrument and means controlled by said pedals for accenting said notes in varying degrees as compared to the remaining synchronously sounded notes of a chord.

27. An expression device for musical instruments comprising a plurality of movable elements, a ported cylinder, and a nippled cylinder coöperating therewith to control said elements, said cylinders being disposed about a common axis, and one being revolvable with respect to the other.

28. An expression device for musical instruments comprising a plurality of movable elements, a series of parts for moving said elements, pneumatic means for actuating said parts, a member mounted for rotation and also for translation, means coöperating with said parts whereby the rotation and translation of said member controls the action of said parts, and means for rotating and translating said member.

29. An expression device for musical instruments comprising a plurality of movable elements, a series of parts for moving said elements, a substantially fixed member and a member movable in two ways, a point carried by said member being variously positionable within the limits of a predetermined surface, means whereby the position of parts of such member with respect to said fixed member determines the relative positions of said movable elements, and pneumatic means controlled by said member for actuating said parts and thereby said elements in manner aforesaid.

30. An expression device for musical instruments comprising a plurality of movable elements, a series of parts for moving said elements, a plurality of members, one of said members being relatively movable with respect to another of said members, a point carried by one of said members being variously positionable within the limits of a predetermined surface, means whereby the position of parts of such member with respect to another of said members determines the relative positions of said movable elements, said means including pneumatic connections controlled by said member for actuating said parts and thereby said elements in manner aforesaid.

31. In an expression device for automatic instruments, means for effecting a relative difference in intensity of tone between notes sounded by an instrument, a controlling device for said means, said device comprising a plurality of parts relatively movable with respect to each other, means for effecting step by step movement of one of said parts

in one direction or in the reverse of said direction, and means for effecting step by step movement of one of said parts in a manner at variance with that of either of 5 the movements aforesaid.

32. In an expression device for automatic and semi-automatic instruments, means for effecting a relative difference in intensity of tone between notes sounded by an instrument, a controlling device for said means, said device comprising a plurality of parts relatively movable with respect to each other, means for effecting step by step movement of one of said parts in one direction, 10 and means for effecting step by step movement of one of said parts in another and diverse direction.

33. An expression device for automatic instruments comprising a plurality of pneumatics, an element movable by the action of said pneumatics in a number of directions, said number being greater than two, and locking means disposed for engagement with said element, said means adapted to 20 hold said element substantially against movement when the latter is in any one of a plurality of positions.

34. In musical apparatus, adjustable means for varying the accentuation at different points of the musical scale, a power-actuated device having a plurality of separately-actuable sections for moving said adjusting means, means for controlling the actuation of said sections in various combinations to effect different adjustments of 30 said actuating means; and pneumatically controlled means for holding said adjusting means against inadvertent displacement when set for a given accentuation.

35. In musical apparatus, adjustable means, parts of which are relatively displaceable with respect to each other in a plurality of diverse ways, for varying the accentuation at different points of the musical scale, a plurality of power actuated devices each comprising a plurality of separately-actuable sections for operatively setting said adjusting means, one of said devices adapted to displace one of the said 40 parts of the adjustable means in one way and another of said devices adapted to displace one of said parts in another of said diverse ways, and means for controlling the actuation of said sections in various combinations to effect different adjustments of 50 said parts with respect to each other.

36. An expression device for automatic instruments comprising a pneumatic, an engageable element movable by the action of 60 said pneumatic, frictional retaining means disposed for engagement with said element and adapted to hold it against inadvertent displacement, and pneumatic means for controlling said frictional retaining means.

37. An expression device for automatic

instruments comprising a pneumatic, an engageable element rotatable about an axis by the action of said pneumatic, and clamping means disposed for engagement with said element, said means adapted to operatively engage said element when the latter is in any one of a plurality of positions into which it may have been rotated.

38. An expression device for automatic instruments comprising a pneumatic, an engageable pivotally mounted element movable rotarily by the action of said pneumatic, a brake disposed for engagement with said element, and means for releasing said brake prior to the actuation of said 75 pneumatic.

39. In player-pianos and the like, note sounding pneumatics, a tracker having apertures therein adapted for co-action with a perforated music roll, means connected to 80 said pneumatics for controlling the respective note sounding pneumatics, auxiliary pneumatics including a brake pneumatic, connections between said tracker and said auxiliary pneumatics, accenting means controlled by said auxiliary pneumatics, and means adapted for co-action with said brake pneumatic for clamping a part of said accenting means against inadvertent displacement.

40. In musical instruments the playing of which is controlled by a music roll, a series of note sounding parts, actuating means for said parts controlled by said music roll, and an expression device for controlling the accentuation of notes, comprising a rotatable and translatable member, and automatic mechanism also controlled by said music roll for rotating and translating said member.

41. In musical instruments, note sounding devices, pneumatic appliances for actuating said devices, means for operating said appliances comprising a plurality of substantially independent systems, each of said systems having its own air pumping means, a pedal, and connections between said pedal and parts of said air pumping means whereby one portion of the stroke of said pedal effects a different operative relationship between two of said air pumping means from 100 that effected by another portion of said stroke, and selective means for placing said pneumatic appliances in communication with one or another of said systems.

42. In musical instruments, note sounding devices, pneumatic appliances for actuating said devices, means for operating said appliances comprising a plurality of substantially independent systems, each of said systems having its own means for varying 110 the pressure of the air in the parts thereof, a pedal, and mechanism whereby the movement of said pedal will effect a variation in pressure of air in the respective systems 120 aforesaid in different degrees, and selective 125 means for placing said pneumatic appliances in communication with one or another of said systems.

mechanism for placing said pneumatic appliances in communication with one or another of said systems.

43. A pneumatically operated musical instrument comprising material disposed to form a series of cells, a plurality of conduits having ported connections with said cells, pneumatically operated parts for placing variable numbers of said cells into and out of communication with one of said conduits, and mechanism for controlling said pneumatically operated parts comprising a port controlling device and means for mounting said device for movement in a plurality of diverse ways.

44. A pneumatically operated musical instrument comprising material disposed to form a series of cells, a plurality of conduits having ported connections with said cells, pneumatically operated parts for placing variable numbers of said cells into and out of communication with one of said conduits, and mechanism for controlling said pneumatically operated parts including a port controlling device movable in a plurality of diverse ways and means for moving said device in said diverse ways.

45. In pneumatically operated musical instruments having tone sounding mechanisms controlled by a perforated music roll, an expression device comprising a series of valve parts, and a controlling device therefor, having as elements thereof a ported structure and a single coöperating member, both of which are distinct from said perforated roll and one of which parts is movable with respect to the other, a determinably variable number of said valve parts being displaced and set apart from the remaining parts of said series in accordance with such movement, means controlled by said movable part for displacing variable numbers of said valve parts in manner aforesaid, said variable numbers being of any desired size and being displaced wherever desired in said series in accordance with the relative disposition of said member to said structure, and automatic indicating mechanism for rendering plainly evident the number of valve parts affected at any given time and the disposition of said number in said series.

46. In pneumatically operated musical instruments having tone sounding mechanisms

controlled by a perforated music roll, an expression device comprising a series of valve parts, and a controlling device therefor having as elements thereof a ported structure and a single coöperating member, both of which are distinct from said perforated roll and one of which parts is movable with respect to the other, a determinably variable number of said valve parts being displaced and set apart from the remaining parts of said series in accordance with such movement, means controlled by said movable part for displacing variable numbers of said valve parts in manner aforesaid, said variable number being of any desired size and being displaced whenever desired in said series in accordance with the relative disposition of said member to said structure, and separate means for indicating the number of valve members affected at any given time and the disposition of said number in said series.

47. In pneumatically operated musical instruments having tone sounding mechanisms controlled by a perforated music roll, an expression device comprising a series of valve parts, and a controlling device therefor having as elements thereof a ported structure and a single coöperating member, both of which are distinct from said perforated roll and one of which parts is movable with respect to the other, a determinably variable number of said valve parts being displaced and set apart from the remaining parts of said series in accordance with such movement, means controlled by said movable part for displacing variable numbers of said valve parts in manner aforesaid, said variable number being of any desired size and being displaced wherever desired in said series in accordance with the relative disposition of said member to said structure, and means controlled by said music roll for automatically effecting the desired relative disposition of said member to said structure.

In witness whereof, I subscribe my signature, in the presence of two witnesses.

CHARLES P. HIDDEN.
